Howard M. Cohn(57) **CLAIM**

The ornamental design for a vacuum cleaner as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the vacuum cleaner where the vacuum cleaner is in a configuration of use;

FIG. 10 is an enlarged view of portion 10 shown in FIG. 1; and,

FIG. 11 is an enlarged view of portion 11 shown in FIG. 2. The dash-dash broken shown in the drawings depict the bounds of the claimed design, while all other dash-dash broken lines shown in FIG. 9 are directed to environment, and the dash-dash broken lines form no part of the claimed design. The dot-dash broken lines in FIGS. 1-2, and 10-11 represent boundaries of the enlarged portions and form no part of the claimed design.
